PAPER LOG ROLLER

Louis J. Christen, Jr., St. Louis, Mo., assignor to
Christen Incorporated, St. Louis, Mo.

Filed Aug. 30, 1974, Ser. No. 501,861

Term of patent 14 years

Int. Cl. D8—05

U.S. Cl. D8—222

FIG. 1

FIG. 2

FIG. 3

FIG. 4

FIG. 1 is an end elevational view of a paper log roller showing my new design.

FIG. 2 is an opposite end elevational view from that shown in FIG. 1.

FIG. 3 is a front side view thereof.

FIG. 4 is a top plan view thereof.

I claim:

The ornamental design for a paper log roller, as shown.
